[57] ABSTRACT

A device for detecting a bend angle upon precisely bending a metallic pipe to be used in a method for bending a pipe in which precise bending is achieved by detecting a deviation of a distance between one point on said pipe to be bent and a fixed point outside of said pipe from another distance between a predetermined locus and said fixed point by means of an arm having its opposite end portions pivotably supported at said one point and said fixed point respectively, characterized in that there is provided means for detecting a sum of a rotational angle of said arm about said fixed point as the bending proceeds since the beginning of the bending work and an angular variation at the portion of said arm joined to said pipe to obtain a true bend angle.

DEVICE FOR DETECTING A BEND ANGLE UPON PRECISELY BENDING A METALLIC PIPE

The present invention relates to a device for detecting a bend angle to be used in an apparatus for precisely bending a metallic pipe.

With regard to a method for precisely bending a metallic pipe, there has been proposed a method as illustrated in FIG. 1, which is described and claimed in the copending U.S. Pat. Application of Omori et al Ser. No. 289,212 filed Sept. 13, 1972. In this figure, a deviation of a distance between one point B on a pipe A to be bent and a fixed point C outside of said pipe from another distance between a predetermined locus and said fixed point C, is detected by means of an arm D having its opposite ends pivotably supported at said respective points B and C, and in accordance with the detected signal the forth and back movement of a press roll E is controlled to achieve precise bending. In such a case, normally the angle $\angle\theta_1$, has been deemed as a bend angle. However, it has been found that in a actual bending work, the relation $\angle\theta_1 = \angle\theta_2$ is not continuously true, in other words, the angle $\angle\theta_3$ is continuously varying by a minute amount during the bending work.

One object of the present invention is to provide a device for detecting a true bend angle upon precise bending in view of the above-referred disadvantage in the prior art. To this end, the invention provides a device for detecting a bend angle upon precisely bending a metallic pipe to be used in a method for bending a pipe in which precise bending is achieved by detecting a deviation of a distance between one point on said pipe to be bent and a fixed point outside of said pipe from another distance between a predetermined locus and said fixed point by means of an arm having its opposite end portions pivotably supported at said one point and said fixed point respectively, characterized in that there is provided means for detecting a sum of a rotational angle of said arm about said fixed point as the bending proceeds since the beginning of the bending work and an angular variation at the portion of said arm jointed to said pipe to obtain a true bend angle.

In the drawings; FIG. 1 is a schematic view showing the outline of an apparatus for precisely bending a metallic pipe,

FIG. 2 is a schematic view for representing the relation between the true bend angle and the rotational angle of the rotary shaft at the fixed point in the apparatus shown in FIG. 1.

FIG. 3 is a schematic view showing one preferred embodiment of the present invention.

As shown in FIG. 2, if the angle between the arm D and the pipe axis in the beginning of the bending work is represented by $\angle\theta_3'$, the corresponding angle during the progress of the bending work is represented by $\angle\theta_3''$, the rotational angle of the arm about the fixed point during this period of time is represented by $\angle\theta_1$, and the true bend angle is represented by $\angle\theta_2$ then

Thus, one feature of the present invention exists in that in order to precisely detect the true bend angle $\angle\theta_2$ in the final state, during the progress of the bending work the true bend angle $\angle\theta_2$ is continuously detected by continuously detecting the sum of $\angle\theta_1$, and $(\angle\theta_3'' - \angle\theta_3')$.

Now the present invention will be described in connection to one preferred embodiment with reference to the accompanying drawings.

In FIG. 3, as a pipe 4 is pushed into the bender by a pressing force P, said pipe 4 is bent in the region between a support point 1 and a press point 2 while said press point is successively advanced to the position 2', where said pipe is in the state represented by a numeral 4'. In this arrangement, in order to bend the pipe, there are provided known high frequency induction heating device 5 and a known cooling device 6 to be used after bending.

In addition, reference numeral 3 designates guide rolls, numerals 7, 7' designate a deviation detector, numeral 8 designates a sticker to the pipe, reference C designates a fixed point outside of the pipe, and $\angle\theta_1$, $\angle\theta_2$, $\angle\theta_3'$ and $\angle\theta_3''$ represent the same angles as those shown in FIG. 2.

Although the bending itself can be attained in a simple manner through the above-described method, it is difficult to determine the true bend angle $\angle\theta_2$ of the pipe. However, since the relation of $\angle\theta_2 = \angle\theta_1 + (\angle\theta_3'' - \angle\theta_3')$ can be proved geometrically in the above-described arrangement, it is only necessary to measure and control the values appearing on the right side of the above equation.

In the above arrangement, $\angle\theta_1$ is obtained by detecting the rotational angle of the rotary shaft at the fixed point by means of a resolver or the like, and the angle variation at the joint between the pipe and the arm represented by $(\angle\theta_3'' - \angle\theta_3')$ is obtained by providing a detector of a rotational angle (such as a resolver) on the rotary shaft of the sticker 8 to the pipe and by setting the reading of the resolver for the initial value of $\angle\theta_3'$ in the beginning of the bending work at 0°. In other words, as the bending proceeds, the value of $\angle\theta_1 + (\angle\theta_3'' - \angle\theta_3')$ is electrically detected and the true bend angle $\angle\theta_2$ is measured on the basis of said detected value. Furthermore, if the bending work is automatically (or manually) stopped when the measured true bend angle has become coincident with a preset angle, it is possible to easily obtain a required bend angle.

As described, according to the present invention, the bend angle can be controlled in a precise manner, and so the corrective bending work which needs a lot of steps is not required at all in contrast to the prior art practice.

Through test measurements for the bending achieved by means of the above-described apparatus according to the present invention, we have obtained very favorable results as shown in the following table:

Instructed Value	Actual Bend Angle				
90.0°	90.0°	89.9°	90.0°	90.0°	90.0°
60.0°	60.0°	60.0°	59.9°	60.0°	60.0°
45.0°	45.0°	44.9°	45.0°	45.0°	45.0°

the following relation is established:

$$\angle\theta_2 = \angle\theta_1 + (\angle\theta_3'' - \angle\theta_3')$$

What is claimed is:

1. Apparatus for detecting the bend angle of a pipe having an initially generally straight portion being bent to curved form by longitudinally moving the pipe while applying a lateral force thereto in said portion, said detecting apparatus comprising:

means establishing a first translationally fixed, angularly rotatable axis outside the pipe, laterally spaced therefrom and disposed generally in the imaginary plane normal to the longitudinal axis of the pipe at the juncture between where the pipe remains unbent and where the pipe is being bent;

means establishing a second angularly rotatable axis on the pipe in said portion whereat the bend angle with respect to the longitudinal axis of the pipe at the imaginary plane is to be determined, the second axis being parallel to the first axis;

arm means joining said first and second axes and being so mounted at opposite ends with respect thereto that as the pipe is longitudinally moved in being bent, one end of the arm moves angularly about the first axis in correspondence to the angular movement of the opposite end of the arm about the first axis due to the joining of said opposite end and the pipe at the second axis;

means measuring the angular movement of said arm about the first axis;

means measuring the angle between said arm and the longitudinal extent of the pipe at said second axis; and

means for detecting, as the bending proceeds, the sum of:

a. the angular disparity between the opposite extremes of disposition of said arm due to angular movement about the first axis; and

b. the difference at said opposite extremes of disposition of said first axis of the angle between said arm and the longitudinal axis of the pipe at said second axis;

as a measure of the angular disparity between the dis-

40

position of the longitudinal axis of said pipe axially coincident with said second axis, the angular amount said pipe has been bent at said second axis.

5 2. A method for detecting the bend angle of a pipe having an initially generally straight portion being bent to curved form by longitudinally moving the pipe while applying a lateral force thereto in said portion, said detecting method comprising:

establishing a first translationally fixed point outside the pipe, laterally spaced therefrom and disposed generally in the imaginary plane normal to the longitudinal axis of the pipe at the juncture between where the pipe remains unbent and where the pipe is being bent;

establishing a second point fixed on the pipe in said portion, whereat the bend angle with respect to the longitudinal axis of the pipe at the imaginary plane is to be determined;

tying the rotational disposition of the first fixed point to the second fixed point, so that as the pipe is longitudinally moved in being bent, said first point is correspondingly angularly moved to maintain its angular position fixed relative to said second point;

as the bending proceeds, monitoring the sum of:

a. the angular disparity between the opposite extremes of disposition of said first point; and

b. the difference at said opposite extremes of angular disposition of said first point of the angle between a straight line joining said first and second points and the longitudinal extent of said pipe at said second point;

35 as a measure of the angular disparity between the disposition of the longitudinal axis of said pipe axially coincident with said second point, the angular amount said pipe has been bent at said second point.
